AUTOMATIC CORE LOADER

James P. Gerhart, 1506 Pheasant Drive,
Warminster, Pa. 18974

Filed Feb. 3, 1972, Ser. No. 223,398

Term of patent 14 years

Int. Cl. D15—99

U.S. Cl. D55—1 C

FIG. 1

FIG. 2

FIG. 3

FIG. 4

FIG. 5

FIG. 6

FIG. 1 is a side elevation view of an automatic core loader showing my design;

FIG. 2 is a top plan view of my design taken along the line 2-2 of FIG. 1;

FIG. 3 is a bottom view of my design taken along the line 3-3 of FIG. 1;

FIG. 4 is a side elevation view of the invention showing the side opposite to that shown in FIG. 1;

FIG. 5 is an end view taken along the line 5-5 in FIG. 4; and

FIG. 6 is an end view of my design taken along the line 6-6 of FIG. 4.

I claim:

The ornamental design for an automatic core loader, as shown and described.
